(57) CLAIM

I claim the ornamental design for a rifle scope, as shown and described.

DESCRIPTION

FIG. 1 is a right side perspective view of a rifle scope showing my new design;

FIG. 2 is a left side perspective view of FIG. 1;

FIG. 3 is a right side view of FIG. 1;

FIG. 4 is a left side view of FIG. 1;

FIG. 5 is a top view of FIG. 1; and,

FIG. 6 is a bottom view of FIG. 1.

Stippling shown in the figures represents a band applied on a surface of a rifle scope that forms a contrast in appearance. The broken line portion of the figure drawings is included for the purpose of illustrating environment and forms no part of the claimed design.
